UNITED STATES PATENT OFFICE.

HENRY FREE, OF LEWISTON, MAINE.

IMPROVEMENT IN CAMP-STOOLS.

Specification forming part of Letters Patent No. 115,598, dated June 6, 1871.

To all whom it may concern:

Be it known that I, HENRY FREE, of Lewiston, in the county of Androscoggin and State of Maine, have invented a new and useful Improvement in Camp-Stool; and I do hereby declare that the following is a full and exact description of the same, reference being had to the accompanying drawing and to the letters of reference marked thereon.

This invention has for its main object the production of a camp-stool which shall be capable of being folded in a very small compass when not in actual use; and consists in certain details of construction, which will be fully described hereinafter.

In the drawing, Figure 1 represents a perspective view of the stool ready for use; Fig. 2, the same folded for transportation; and Figs. 3, 4, 5, and 6, views of detached parts.

To enable others skilled in the art to make and use my invention, I will now proceed to describe fully its construction and manner of operation.

A A A represent the legs of a three-legged stool, which are united by means of a triple screw, x, as shown in Fig. 5, and provided with the ordinary seat-straps a a a. The principal peculiarity of the construction consists in providing each leg with a joint, a¹,

and sliding sleeve a², as shown, by which means the legs may be folded together. To hold the sliding sleeve in place a spring, a³, is inserted beneath it, as shown in Fig. 4. By means of this construction a camp-stool may be made small enough to be carried in a pocket.

The operation is easily understood from the drawing.

When it is desired to use the stool, the legs, after being unfolded and secured in place by the sliding sleeves, are spread apart, as shown in Fig. 1. At other times the legs are closed and folded together in a compact bundle.

Having thus fully described my invention, what I claim as new, and desire to secure by Letters Patent, is—

1. A camp-stool, provided with jointed legs, sliding sleeves, and holding-springs, as described.

2. The camp-stool described, having its legs united by a triple screw, the legs being jointed and provided with sliding sleeves, substantially as described.

This specification signed and witnessed this 28th day of April, 1871.

HENRY FREE.
